STRIKING MECHANISM FOR STENOGRAPHIC WRITING-MACHINES.

1,162,688.

Specification of Letters Patent. Patented Nov. 30, 1915.

Application filed December 12, 1912. Serial No. 736,318.

To all whom it may concern:

Be it known that we, ALRAH B. EDWARDS and FRANK K. RUSSELL, citizens of the United States, residing at Dallas, in the county of Dallas and State of Texas, have invented certain new and useful Improvements in Striking Mechanism for Stenographic Writing-Machines, of which the following is a specification.

Our invention relates to stenographic typewriting machines, and relates more particularly to a striking mechanism for such machines.

The object of our invention is to provide a striking mechanism for stenographic typewriting machines which mechanism will be rendered almost noiseless in operation by mounting the type-carrying extremities of the striking members or type bars closely adjacent to the platen, so that the stroke of the type bars will be the least possible.

Another object is to provide a simple means for engaging each type bar with a pivoted universal bar, the latter being acted upon by a spring which will cause any type bar to be returned to its normal position after having been displaced through the striking of a key.

A further object is to provide a striking mechanism for a stenographic typewriting machine, the parts of which mechanism will have an extreme simplicity and will be adapted to be assembled or taken apart with comparatively small expenditure of time and labor.

With these and various other objects in view, our invention has relation to certain novel features of the construction and operation, an example of which is described in the following specification, and illustrated in the accompanying drawings, wherein:

Figure 1 is a top or plan view of the mechanism comprising the herein described invention, such parts of the typewriting machine as are not directly correlated with said invention, being omitted from this view. Fig. 2 is a vertical, sectional view of the invention, showing a portion of the frame of the typewriter, the plane of section being taken parallel to the side walls of the machine.

Referring now more particularly to the drawings, wherein like reference characters designate similar parts in both the figures,

the numeral 1 denotes a plurality of key levers pivotally mounted between the side walls 2 of the machine casing, said levers being slightly spaced from the surface which supports the machine. The rear extremities of the levers 1 are pivotally mounted upon a rod 3 transversely extending between the rear portions of the side walls 2, slots 4 being provided in the upper edges of said levers to receive said rod. A wire spring 5 is correlated with each lever 65 1 at the rear extremity thereof, said spring serving the dual purpose of holding the lever in its proper relation to the rod and returning the lever to its normal position after having been subjected to a downward, angular displacement. The middle portion of each spring 5 rests transversely upon the rod 3 adjacent to the correlated lever, and the forward and rearward extremities of each spring are respectively hooked beneath the 75 correlated lever and beneath a rod 6 parallel to the rod 3 and slightly spaced to the rear thereof. The forward extremity of each lever 1 carries the usual key or finger button 7. The rear portions of the key 80 levers 1 are parallel and spaced an equal distance apart, while the forward extremities of said levers are diverged from each other in fan shape. A short space above the middle portions of the key levers 1, a rod 8 85 is transversely extended between the side walls 2 of the machine, and upon this rod are pivotally mounted the lower extremities of a plurality of substantially upright type bars 9, each having an integral, rearwardly 90 extending arm 10 provided to its lower portion, the free end of which arm is connected with the middle portion of the correlated key lever by a swinging link 11.

In order to facilitate the assembling and repairing of the machine, the pivotal mounting of the type bars is accomplished by providing each bar at its lower end with a slot 12 receiving said rod. A wire spring 13 is correlated with each type bar to hold the 100 same in proper relation to the rod 8, the fixed extremities of the springs 13 being mounted upon a plate 14 extending horizontally between the side walls 2. The matter above described is also set forth in a co- 105 pending application, Serial No. 736,320.

Upon the rod 8 there is also pivoted the lower extremity of an upright support for

a universal bar 15, which is subjected to a forwardly acting impulse by an inclined coiled spring 16, having one extremity secured to the upper portion of said universal bar and the other extremity secured to the forward edge of the plate 14. The upper horizontal portion of the universal bar is engaged by a plurality of hooks 17, one of which projects forwardly from the middle 5 portion of each type bar 9. The connection thus established between each type bar and the universal bar is such that a rearward angular displacement of any type bar will be communicated by the hook 17 of said 10 type bar to the universal bar, but this rearward displacement will not be communicated by the universal bar to any of the other type bars. After any type bar has completed its stroke, it will be automatically 15 returned to its normal position due to the rearward movement to which the universal bar is subjected by the spring 16. The type, one of which is provided at the upper extremity of each bar 9, is indicated by the 20 numeral 18. The inking ribbon 19, platen 20, paper 21 and paper roll 22 may not properly be considered features of the striking mechanism, but they are shown in the 25 drawings to more readily explain the construction and operation of the invention. It is to be observed that the type bars 9 are parallel and equidistant, the space between said bars being considerably less than that 30 which separates the parallel portions of the key levers. The leverage provided by the 35 key levers 1 is such that a very light touch is sufficient to operate the striking mechanism above described.

The invention is presented as including 40 all such modifications and changes as properly come within the scope of the following claims.

What we claim is:

1. In a stenographic type-writing machine, the combination with a plurality of key levers, of a horizontal rod upon which the rear extremities of said levers are pivoted, a rod parallel to the first mentioned rod, transversely extending above the middle portions of the key levers, a plurality of type-bars equal in number to the key-levers, pivoted upon the last mentioned rod, an arm projecting rearwardly from each type-bar, a universal bar pivoted upon the last mentioned rod, a hook projecting forwardly from each type-bar and engaging the universal bar, producing a displacement of the latter bar when any key is struck, and means for automatically returning the universal 60 bar to its normal position, after any key has been struck.

2. In a striking mechanism for steno-

graphic type-writing machines, the combination with a plurality of key levers pivoted at their rear ends, of a plurality of type-bars, a hook projecting from each type-bar, a transverse universal bar, pivoted uprights supporting the universal bar at their upper ends, said hooks normally engaging the universal bar, a coiled spring connected to the universal bar and to a stationary member, projections on the type-bars, and links attached to the key levers and the projections of the type-bars.

3. In a striking mechanism for stenographic type-writing machines, the combination with a plurality of key levers pivoted at their rear ends, of a plurality of type-bars, a hook projecting from each type-bar, a transverse universal bar in the path of the hooks, pivoted uprights supporting the universal bar at their upper ends, the hooks normally engaging the universal bar, a coiled spring connected to the universal bar and to a stationary member, projections on the type-bars, links attached to the key levers and the projections of the type-bars, and spring members engaging the type-bars and holding the same in normal position.

4. In a striking mechanism for stenographic type-writing machines, the combination with a plurality of key levers pivoted at their rear ends, of a plurality of type-bars having pivot points closely associated and provided with projections, each projection except one at the center of the machine being directed laterally toward a correlated key lever, a connection from each type-bar projection to its respective key lever, and a swinging universal bar associated with the closely associated portions of the type-bars.

5. In a striking mechanism for stenographic type-writing machines, the combination with a plurality of key levers pivoted at their rear ends, a plurality of type-bars having pivot points closely associated and provided with projections, each projection except one at the center of the machine being directed laterally toward a correlated key-lever, a connection from each type-bar projection to its respective key lever, a swinging universal bar mounted adjacent the type-bars, and hook extensions on the closely associated portions of the type-bars engaging the universal bar.

In testimony whereof we have signed our names to this specification in the presence of two subscribing witnesses.

ALRAH B. EDWARDS.
FRANK K. RUSSELL.
